UNITED STATES PATENT OFFICE.

ALEXANDER J. RUSAK, OF BROOKLYN, NEW YORK, ASSIGNOR TO THE MARVEL DEVICE CORPORATION, OF BROOKLYN, NEW YORK, A CORPORATION OF NEW YORK.

HAIR-WAVING DEVICE.

Application filed June 16, 1928. Serial No. 285,972.

This invention relates to a hair waving device, and relates more particularly to a device for producing either water or plain waves, or Marcel waves.

5 The principal object of the invention is the provision of a device including a plurality of similar hair waving units which may be quickly engaged with the hair for the intended purpose, and which may be 10 used optionally to produce water or plain waves, or Marcel waves, the device including means whereby the hair waving units may be held associated with each other in staggered relationship engaged with the 15 hair, for producing Marcel waves, as distinguished from the water or plain waves, which are produced by using the hair waving units alone.

Another object of the invention is the provision of a hair waver embodying improvements in construction whereby the waver will more effectively wave the hair, which will be comfortable to the user, and which will be easy on the hair.

25 The nature of the invention and its distinguishing features and advantages will appear when the following specification is read in connection with the accompanying drawing, in which

30 Figure 1 is a view of a plurality of hair waving units engaged with the hair in staggered relationship, to produce Marcel waves.

Fig. 2 is a transverse sectional view of one of the units taken on the line 2, the section being on an enlarged scale.

Fig. 3 is a view of one of the hair waving units, the same being shown open.

Fig. 4 is a longitudinal sectional view through a portion of one of the hair waving units, the section being taken on the line 4 of Fig. 1.

Fig. 5 is a view of one of the spacers.

Generally stated, the device of the present invention comprises a plurality of hair waving units 10, and spacers 11 which serve in conjunction with the units 10 for the purpose of maintaining the units 10 associated with each other in staggered relationship when engaged with the hair for the purpose of producing Marcel waves in the hair. The spacers 11 may be readily engaged with the units 10 to hold the units associated with each other for the purpose mentioned, and said spacers 11 may also be readily detached. It is to be understood

that it is within the present invention to use the hair waving units 10 without the spacers 11 when it is desired to produce what is known as water or plain waves.

The hair waving units 10 are of similar 60 construction, therefore a description of the construction of one will suffice for all. The hair waving unit 10 is of arcuate shape longitudinally considered. The unit 10 comprises longitudinally arcuate hair waving 65 members which cooperate with each other, there being a lower member 12 and an upper member 13. The lower member 12 is concavo convex in cross section substantially throughout its length, and is provided at 70 one end with an upstanding lug or terminal 14 having a hole 15 therein. The opposite end of the member 12 is provided with a finger piece 16 having a hole 17 therein which presents an edge 18 for a purpose to 75 appear. One longitudinal edge of the member 12 is provided with crimps or corrugations 19, and the opposite longitudinal edge is also provided with crimps or corrugations 20. These crimps or corrugations 19 80 and 20 prevent the hair from sliding sideways along the members 12 and 13 when they are brought together in engagement with the hair. The member 12 is also provided with a series of elongated openings 21 which extend transversely of the central portion of the member 12, and said member 12 is also provided with a series of perforations 22 adjacent the longitudinal edge having the corrugations 19. The end of the member 12 85 having the terminal 14 is provided with a pivot 23 which may be secured at the opposite ends in any practical manner. The upper member 13 is of substantially the same form as the member 12 and is designed to cooperate therewith and fit with in the same. The member 13 is concavo convex in cross section substantially throughout its length, and has an eye 24 formed at one end, and the opposite end thereof is 90 provided with a spring lip or roll 25. A channel 26 is formed along one longitudinal edge of the member 13 which presents a continuous longitudinal flange 27. The flange 27 is provided with crimps or corrugations 28 which correspond to the corrugations 19 of the member 12. The opposite longitudinal edge of the member 13 is left plain or without corrugations. The central portion of the member 13 is provided with 95

crimps or corrugations 29 similar in number and arrangement to the openings 21 in the member 12 to distend the strands of hair when the members 12 and 13 are brought together in crimping engagement to prevent the hair from slipping sidewise along the members when they are brought together in engagement with the hair. The member 13 is provided with a multiplicity 10 of airholes 30. The eye 24 of the member 13 receives the pivot 23 on the member 12, and in this way the members 12 and 13 are connected together for pivotal movement with respect to each other. The spring lip 15 or roll 25 is positioned on the member 13 so as to coat with the edge 18 on the member 12 to releasably hold the member 13 in clamping engagement with the member 12 when the hair is arranged between the said 20 members. The members 12 and 13 are made preferably of aluminum.

Each of the spacers 11 hereinbefore referred to is made of aluminum and is struck from a single piece to provide lugs 31, two 25 of which are offset with respect to a third lug.

When it is desired to produce water or plain waves, a sufficient number of the hair waving units 10 are engaged with the hair side by side and are left to remain until such 30 time as the hair has become waved. The openings 21, and perforations 22 and 30 respectively in the members 12 and 13 allow air to circulate and aids in producing the waves in conjunction with the crimps or corrugations 19, 20, 28 and 29 together with the general concavo-convex cross sectional shape, and the longitudinal arcuate shape of the members 12 and 13.

40 When it is desired to produce Marcel waves, a sufficient number of units 10 are engaged with the hair 10, and alternate units 10 are disposed in staggered relationship with respect to the others, and are held in 45 this manner by the spacers 11, the lugs 31 of which are engaged respectively in the holes 15 of the terminals 14, as shown most clearly in Fig. 1.

I claim:

50 1. In a hair waver, a pair of cooperating waving members, one of said members being provided with a continuous channel and corresponding flange along one of its longitudinal edges, said flange being corrugated, 55 and one longitudinal edge of the other member, which enters said channel, being corrugated complementary to the corrugations of said flange.

2. A hair waver comprising a pair of cooperating waving members having complementary corrugations and being concavo-convex in cross section, a pivot connecting one end of one member with one end of the other member, whereby said members have pivotal movement with respect to each other, and means at the free ends of said members for detachably securing said members in clamping engagement with the hair, said corrugations preventing the hair from slipping sidewise along said members when they are engaged with the hair. 60

3. In a hair waver, a pair of cooperating waving members having complementary corrugations extending transversely thereof, and said members being concavo-convex in cross section, said corrugations preventing the hair from slipping sidewise along said members when they are engaged with the hair. 65

4. In a hair waver, a pair of cooperating longitudinally arcuate waving members, concavo-convex in cross section and provided with complementary corrugations on side edges of the members to prevent the hair from slipping sidewise along said members when they are engaged with the hair. 70

5. A hair waver comprising a pair of cooperating waving members pivotally connected together, one of said members having a channel and corresponding flange along one of its longitudinal edges, and the other member having a longitudinal edge which enters said channel to cooperate with said flange to prevent the hair from sliding sidewise along said members when they are brought into engagement with the hair, and means for securing said members in clamping engagement with the hair. 75

6. A hair waver comprising a pair of cooperating waving members pivotally connected together, one of said members having corrugations and the other member having openings which respectively register with the corrugations when the members are engaged with the hair, to prevent the hair from sliding sidewise along said members, and means for securing said members in clamping engagement with the hair. 80

Signed at New York in the county of New York and State of New York this 14th day of June A. D. 1928.

ALEXANDER J. RUSAK.
